F. A. LUNDQUIST.
AUTOMATIC SWITCH,
APPLICATION FILED FEB. 12, 1917.

Patented Jan. 1, 1918.

Inventor:
Frank A. Lundquist
by *A. C. Gruenert, Atty.*

UNITED STATES PATENT OFFICE.

FRANK A. LUNDQUIST, OF CHICAGO, ILLINOIS, ASSIGNOR TO WESTERN ELECTRIC COMPANY, INCORPORATED, OF NEW YORK, N. Y., A CORPORATION OF NEW YORK.

AUTOMATIC SWITCH.

1,251,985.

Specification of Letters Patent.

Patented Jan. 1, 1918.

Application filed February 12, 1917. Serial No. 148,228.

To all whom it may concern:

Be it known that I, FRANK A. LUNDQUIST, a citizen of the United States, residing at Chicago, in the county of Cook and State 5 of Illinois, have invented certain new and useful Improvements in Automatic Switches, of which the following is a full, clear, concise, and exact description.

This invention relates to automatic 10 switches for use in either automatic or semi-automatic telephone exchange systems, and particularly to gravity operated switches of the panel type. In this type of switch, sets of contacts are assembled in large flat-faced 15 banks or panels over which brushes are allowed to drop in a straight line to engage a desired set of contacts. These contacts are multiplied horizontally across the panel to be accessible to a plurality of switches.

20 The object of this invention is to provide a switch of compact construction for rapidly connecting a subscriber's line to an idle trunk.

25 In the preferred embodiment of this invention the contacts of each line are carried on a movable line bar.

30 A feature of this invention is the longitudinal displacing of a line bar in a gravity operated switch to position the contacts of the displaced line bar for arresting the movement of a gravity operated set of brushes.

35 Another feature is the longitudinal displacing of the brushes to engage contacts on the displaced line bar.

Other features of the invention will be 40 apparent from the following description and the appended claims.

Referring to the drawing, a perspective view of a switch employing this invention is 45 shown with suitable circuit arrangements for operating it.

In the embodiment of the invention herein disclosed any number of switches may be 50 mounted side by side, as desired, each switch being placed before multiple sets of contacts of a group of terminal strips.

55 In the drawing 1 represents a frame in which a vertical rod 2 is rigidly secured. A yoke-shaped member 3 is slidably mounted on this rod 2 and has the teeth 4 with which a holding pawl 5, pivotally mounted on the frame 1 engages to hold the yoke 3 in its normal position.

55 A pin 6 on the yoke 3 normally engages

one end of a bell-crank lever 7. This lever 7 has at its other end a flat spring 8 which normally engages an arm of a stepping pawl 9. This pawl 9 is pivotally mounted on the arm 10 of the armature of magnet 11, 60 so that when magnet 11 is energized the pawl 9 engages the holding pawl 5 to release the yoke 3 instead of engaging the teeth 4 to move the yoke 3 upward. A vertical rod 12 is slidably mounted in the frame 1 and 65 is normally held against the lower arm of the yoke 3 by a spring 13, one end of which is fastened to the rod 12, and the other end is fastened to the upper arm of the yoke 3. Teeth 14 are cut in the rod 12 and a holding 70 pawl 15 is arranged to engage these teeth. A lug 16 is fastened to the rod 12 and controls a bell-crank lever 17 for a purpose hereinafter described.

A block of insulation 18 is rigidly secured to the rod 12 in any suitable manner. A pair of brushes 19 and 20, fastened together with a strip of insulation between them, are attached to the block 18 in such a manner that they have a longitudinal 75 movement and also a lateral movement. A pin 22 secured to the block 18 serves as a stop against which the brushes are normally held by a spring 23, one end of which is fastened to the pin 22 and the other end is 80 fastened to a pin 24 secured to the brushes. A slot 21 is provided in the brushes to allow them to be moved longitudinally. A spring 25 engages the side of the brush 20 to return the brushes to their normal position after 85 they have been moved side-wise in a manner hereinafter described. A lug 26 on the brush 20 is so arranged that when the brushes are moved longitudinally by armature 28 of magnet 29 the lug engages a projection 27 of the block 18 to hold the brushes 90 in their operated position.

The brushes 19 and 20 are arranged to engage contacts of a group of line bars generally designated 30. Each line bar 100 consists of two thin metal strips 91 and 92 with a thin insulation strip between them held together in any suitable manner. Each metal strip has a plurality of contacts thereon and each contact of the strip 91 has a hole therein with which a projection 33 of the brush 20 engages for a purpose hereinafter described. Each line bar is pivotally mounted 105 in the frame and also arranged to be moved longitudinally.

Each line bar is individual to a line and has a magnet 34 associated therewith. This magnet becomes energized whenever a call originates on the associated line and by attracting its armature 35 moves the line bar to position the contacts thereof so that they are in the path of the brushes of the switch. There are as many switches per group of lines as the traffic requires.

- 16 The operation of the switch is as follows:
 16 When the subscriber A removes his receiver a circuit for relay 36 is closed from ground, battery, winding of relay 36, conductor 37, contact springs 38 and 39, conductors 40 and 42, subscriber's substation apparatus, conductor 43, resistance 44, to ground. Relay 36 becomes energized and closes at its armature and front contact a circuit for magnet 34, from ground, battery, front contact and armature of relay 36, winding of magnet 34, to ground. Magnet 34, by attracting its armature 35, longitudinally moves the line bar 30 associated with the calling subscriber's line so that contacts thereof are in the path 25 of the brushes of the selected switch. The armature 35 also moves spring 45 to close a circuit for magnet 11 from ground, battery, contact springs 46, 45 and 47, starter wire 48, contact springs 49 and 50, conductor 51, 30 left-hand armature and back contact of relay 52, conductor 53, winding of magnet 11, to ground. Simultaneously a circuit is closed for magnet 29 from ground, battery, contact springs 46 and 45, starter wire 54, contact 35 springs 55 and 56, conductor 57, winding of magnet 29, to ground. Magnet 29, by attracting its armature 28, longitudinally moves the brushes 19 and 20 to position them so that they will engage contacts of the displaced line bar. The brushes are held in 40 their operative position by the lug 26 engaging the catch 27.

Magnet 11, upon becoming energized over the circuit previously described, attracts its armature 10, which moves the pawl 9 upward under the control of spring 8, to engage and withdraw holding pawl 5 from the teeth 4. The brushes 19 and 20 will then be free to drop by gravity into engagement with the 45 contacts 31 and 32 of the displaced line bar 30. The catch 58 of the armature 10 engages a projection 59 of the spring 49 to maintain the contact between springs 49 and 50 closed as long as magnet 11 is energized.

55 As soon as the yoke 3, which slides down with brushes, leaves its normal position the bell-crank lever is moved against the stop 70 by spring 71. This movement of the bell-crank lever closes contact springs 66 and 67 and also moves spring 8 into a position to allow pawl 9 to engage teeth 4 so that when the magnet 11 is subsequently operated the yoke 3 will be stepped upward. Since the magnet 11 is at this time energized over the 65 circuit above described the pawl 9 is pre-

vented from engaging the teeth 4 because it is held in the notch in the lower portion of the pawl 5 into which it was moved by the first energization of the magnet 11.

When the brushes 19 and 20 are stopped 70 by engaging contacts 31 and 32 of the displaced line bar, the weight of the rod 12 and the apparatus attached thereto is carried by the brushes and the line bar and this weight is sufficient to bend the brushes upward so 75 that the lug 26 disengages the catch 27 and allows the brushes to be moved slightly to the left, a distance determined by the pin 33, and the size of the oval-shaped hole in the contact 31, and the weight of the rod 12 also 80 causes the line bar to rotate so that its arm 59 slips off the arm 60 of the armature 35. The spring 61 then moves the line bar back to its normal longitudinal position, thereby 85 moving the contacts thereon out of the path of subsequently operated switches.

Since the pin 33 is in the hole of the contact 31 the brushes 19 and 20 will be moved sideways by this movement of the line bar. The rotation of the line bar also separates 90 contact springs 38 and 39, thereby opening the circuit of relay 36, which by becoming de-energized opens the circuit of magnet 34. Magnet 34 by retracting its armature 35 causes springs 45, 46 and 47 to separate from each 95 other, thereby opening the circuits of magnets 11 and 29. The magnet 29 by retracting its armature allows the bell-crank lever 17 to engage the stop 73. This lever 17 was released by the lug 16 as soon as the rod 12 100 left its normal position, but was prevented from moving by the attracted armature 28. The retraction of the armature 28 also moves the pawl 15 into engagement with the teeth 14 to prevent the rod 12 and brushes 105 thereon from moving back to their normal position. Rod 17, by moving from its normal position, opens the contact between springs 55 and 56 and closes the contact between 56 and 74, and between springs 55 and 75. The closure of springs 55 and 75 extends the starter wire 54 to the next idle switch.

Upon engagement of the brush 19 with contact 32 a circuit for relay 62 is closed 115 from ground, battery, winding of relay 62, conductor 63, brush 19, contact 32, terminal strip 92, conductor 42, subscriber's substation apparatus, conductor 43, resistance 44, to ground. Relay 62 becomes energized and 120 closes a circuit for relay 52 from ground, battery, armature and front contact of relay 62, conductor 64, winding of relay 52, to ground. Relay 52 closes at its right-hand armature and front contact a circuit for 125 magnet 11 from ground, battery, right-hand armature and front contact of relay 52, conductor 65, contact springs 66 and 67, conductor 68, contact springs 76 and 77, conductor 78, winding of magnet 11, to ground. 130

Magnet 11 now attracts its armature 10 and the pawl 9 under the control of springs 8 and 79 engages the teeth 4 to raise the yoke 3. Since the circuit for magnet 11 is opened by the attraction of its armature the magnet will be intermittently energized and deenergized until the rack 3 has been stepped back to its normal position, at which time the pin 6 engages the bell-crank lever 7 and opens contact springs 66 and 67, which permanently breaks the circuit for magnet 11. The rod 12 is prevented from moving upward at this time by pawl 15 being in engagement with teeth 14 and, therefore, spring 13 is placed under tension by this upward movement of the rack to return the rod 12 to its normal position upon the release of the switch.

Relay 52 is slow to release its armatures so that it will remain energized during the sending of impulses by the subscriber.

At the end of conversation, the subscriber A replaces his receiver on the hook, thereby opening the circuit of relay 62, which, upon becoming deenergized, opens at its armature the circuit of relay 52. Relay 52, by retracting its armatures, closes a circuit for magnet 29 from ground, battery, right-hand armature and back contact of relay 52, conductor 30, contact springs 74 and 56, conductor 57, winding of magnet 29, to ground. Magnet 29, by attracting its armature 28, withdraws pawl 15 from engagement with teeth 14, thereby allowing the rod 12, carrying the brushes 19 and 20, to return to its normal position. Upon the rod 12 reaching its normal position the lug 16 engages the bell-crank lever 17, thereby opening contact springs 56 and 74, causing the deenergization of magnet 29. The lug 80, in the normal position of the rod 12, closes springs 49 and 50 to connect magnet 11 to the starter circuit so that this switch is now ready for another call.

45 What is claimed is:

1. In an automatic switch, a plurality of line bars, contacts on said line bars, a gravity operated set of brushes to coöperate with said contacts, means for releasing said set of brushes, and means for longitudinally displacing a line bar to position its contacts to arrest the movement of said set of brushes.

2. In an automatic switch, a plurality of line bars, contacts on said line bars, a gravity operated set of brushes to coöperate with said contacts, means for releasing said set of brushes, means for longitudinally displacing a line bar to position its contacts to arrest the movement of said set of brushes, and means responsive to the engagement of the brushes with contacts of said displaced line bar for removing said line bar from the path of subsequently operated sets of brushes.

3. In an automatic switch, a plurality of line bars in which subscribers' lines terminate, one of said line bars being associated with each line, contacts on said line bars, a gravity operated set of brushes arranged when released to traverse and engage said contacts, means operated upon the initiation of a call upon a line for longitudinally displacing the line bar associated therewith to position the contacts thereof in the path of said set of brushes, and means actuated upon the operation of said means for releasing said set of brushes.

4. In an automatic switch, a plurality of contact terminals, a gravity operated set of brushes to coöperate with said terminals, means for releasing said set of brushes, and means for longitudinally displacing said terminals to engage said set of brushes.

5. In an automatic switch, a plurality of line bars in which subscribers' lines terminate, a line bar being associated with each line, contacts on said line bars, a gravity operated set of brushes arranged when released to traverse and engage said contacts, and means operated upon the initiation of a call on one of said lines for simultaneously releasing said set of brushes and for longitudinally displacing said brushes to engage said contacts.

6. In an automatic switch, a plurality of line bars in which subscribers' lines terminate, a line bar being associated with each line, contacts on said line bars, a gravity operated set of brushes arranged when released to traverse and engage said contacts, and means operated upon the initiation of a call on one of said lines for longitudinally displacing the line bar associated with said line, for releasing said set of brushes, and for displacing said brushes to engage contacts on the displaced line bar.

7. In an automatic switch, a plurality of line bars in which subscribers' lines terminate, a line bar being associated with each line, contacts on said line bars, a gravity operated set of brushes arranged when released to traverse and engage said contacts, means operated upon the initiation of a call on one of said lines for longitudinally displacing the line bar associated with said line, for releasing said set of brushes and for displacing said brushes to engage contacts on the displaced line bar, and means responsive to the engagement of the brushes with the last mentioned contacts for removing said line bar from the path of subsequently operated brushes.

8. In an automatic switch, a plurality of line bars, contacts on said bars, a gravity operated set of brushes to coöperate with said contacts, means for releasing said set of brushes, a magnet individual to each of said line bars and arranged to longitudinally displace said line bar to position the

contacts thereof to arrest the movement of said set of brushes.

9. In an automatic switch, a plurality of line bars, contacts on said bars, a gravity operated set of brushes to coöperate with said contacts, means for releasing said set of brushes, a magnet individual to each of said line bars and arranged to longitudinally displace said line bar to position the

contacts thereof to arrest the movement of 10 said set of brushes, and means responsive to the engagement of the brushes with contacts of the displaced line bar for removing said line from the path of subsequently operated brushes.

15

In witness whereof, I hereunto subscribe my name this 6th day of Feb., A. D. 1917.

FRANK A. LUNDQUIST.
